VACUUM CLEANER BRUSH ROLL

Harold W. Schaefer, Bloomington, and William H. Penn, Normal, Ill., assignors to National Union Electric Corporation, Stamford, Conn.

Filed July 23, 1970, Ser. No. 24,086

Term of patent 14 years

Int. Cl. D4—01

U.S. Cl. D49—17

FIG. 1 is a front view of a vacuum cleaner brush roll showing our new design;

FIG. 2 is a top view thereof;

FIG. 3 is an end view as seen from the line 3—3 of FIG. 1;

FIG. 4 is an end view as seen from the line 4—4 of FIG. 1; and

FIG. 5 is a sectional view taken on the line 5—5 of FIG. 2.

We claim:

The ornamental design for a vacuum cleaner brush roll, substantially as shown.
